VENDING MACHINE

Frank M. Moninger, Los Angeles, Calif., assignor to Sportsman's Manufacturing and Distributing Company, Inc., Los Angeles, Calif., a corporation of Nevada

Application October 14, 1936, Serial No. 105,532

8 Claims. (Cl. 312—49)

This invention relates to vending, or dispensing machines, and has for an object the provision of a machine adapted to dispense round or spherical objects. Whereas the device of the present invention has been designed primarily for use in dispensing golf balls, it should be understood that it is of equal utility in vending other round or spherical objects, such as gum or candy in the form of balls, marbles, tennis or other types of balls, or the like. With this broad object in view the present invention constitutes an improvement over that forming the subject matter of Patent Number 1,952,244, issued March 27, 1934, to Clarence F. Grim.

A more detailed object of the present invention is to provide a dispensing machine of the general character described wherein a new principle of operation of the mechanism for releasing a predetermined number of the spherical objects is introduced, among the advantages of which are more prompt and positive release of the objects to be dispensed each time the machine is actuated, and more positive retention of the other objects intended to be kept within the storage magazine, whereby greater assurance is gained that the person operating the machine will receive full measure and not more of the articles to which he is entitled.

A further object is to provide a dispensing machine having, among others, the advantages above referred to, and the operation of which is dependent upon mechanical means only, i. e., does not involve the use of electromagnets or other electrically operated devices, whereby the device is adapted for successful operation without the inconvenience of connecting it to a source of electrical energy, and even in communities where no electrical energy is available.

A further object is to provide an improved and simplified and highly efficient type of storage magazine wherein all the articles to be vended are arranged in a circuitous single row, all portions of which are at all times visible to persons in front of the machine. This is a detail which enhances the value of the vending machine as such, since it is a well known principle of sales engineering that the appeal of objects offered for sale to possible purchasers is greatly increased by exposing those articles to the full view of passers by, thus making them conscious of the desirable features of the articles and impressing upon them their ready availability.

A further object is to provide a vending machine having the above described characteristics, in the design of which particular attention has

been paid to simplicity and economy of construction, without impairing the positiveness and dependability of its operation, not only for the purpose of reducing its cost of manufacture, but also for the purpose of reducing the over-all dimensions of the assembled machine, so as to enlarge the field of its adaptability by increasing the number of locations in which it is adapted to be installed.

The invention possesses other objects and features of advantage, some of which, with the foregoing, will be set forth in the following description of the preferred form of my invention, which is illustrated in the drawings accompanying and forming a part of the specification. It is to be understood that I do not limit myself to the showing made by the said drawings and description, as I may adopt variations of the preferred form within the scope of my invention as set forth in the claims.

Referring to the drawings:

Figure 1 is a view in front elevation of the magazine for the storage of articles to be dispensed by the machine forming the subject matter of the present invention. For the purpose of enlarging this view the magazine is here shown detached from the other elements of the dispensing machine.

Figure 2 is a rear elevation on a reduced scale showing the assembled machine.

Figure 3 is a top plan view.

Figure 4 is a view in end elevation, the direction of view being indicated by the arrow 4 of Fig. 2.

Figure 5 is a detail view in front elevation of the stop mechanism whereby a predetermined number of objects is released from the dispensing machine. For the purpose of clarity of disclosure this mechanism is here shown detached from the remainder of the machine.

Figure 6 is a perspective view of the structure shown in Fig. 5.

Figure 7 is a top plan view of the structure shown in Fig. 5.

Figure 8 is a transverse, vertical sectional view, the plane of section being taken upon the line 8—8 of Fig. 7, and the direction of view being indicated by the arrows.

Figure 9 is a view similar to Fig. 8 but with the plane of section indicated by the line 9—9 of Fig. 7 and the direction of view by the arrows.

Figure 10 is a perspective view of the coin-actuated means for operating the machine and for predetermining the number of objects to be dispensed at each actuation, and also showing a

portion of the mechanism for resetting the machine to put it in readiness for the next actuation.

In terms of broad inclusion the present invention contemplates the provision of a dispensing machine adapted to release a different number of the articles to be dispensed, this number depending upon the manner in which the operator actuates the machine. In other words, by depositing a coin of a certain denomination, in its proper coin slot, a predetermined number of objects will be delivered to the operator, that number being appropriate to the denomination of the coin, whereas if a coin of different denomination is used and deposited in the proper coin slot, a different number of objects will be delivered, this number again being appropriate to the denomination of the coin. The mechanism whereby these results are accomplished is designed to yield an improved and simplified type of construction whereby positiveness of operation is assured so as to prevent all possibility of delivery of more of the dispensed objects than the operator is actually entitled to receive and yet to cause the machine to operate satisfactorily and with the utmost sureness to deliver the proper number of objects.

Whereas the dispensing machine of the present invention is adaptable by slight modification for use in dispensing a wide variety of spherical or round objects, the modification chosen for illustration and description in the present specification is designed to dispense golf balls. It comprises a housing 11, the predominating feature of which is a magazine 12, preferably of rectangular form and relatively thin in comparison to its height and width, inasmuch as it is intended to accommodate thereinside only a single row of the golf balls 13 to be dispensed. Secured to the back of the magazine 12 and adjacent its lower edge is a relatively small housing 14 for the accommodation of the dispensing mechanism; and at one side of the housing 11 is a receptacle 16 having a hinged lid 17 which receptacle is adapted to receive the golf balls 13 released from the magazine 12 and there be made available to the operator.

Inside the magazine 12, the front face of which preferably is formed of glass 17, a plurality of wedge shaped tongues 18 project from both side walls. These tongues 18, which are arranged in alternation with each other, extend not quite all the way across the magazine, thereby leaving an opening 19 at the end of each tongue large enough to permit a golf ball 13 to drop therethrough from the outer end of one tongue 18 to the inner end of the next tongue therebelow. These tongues being wedge shaped, a circuitous or zig-zag path is provided for the single row of golf balls 13, thus making it possible to store a relatively large number of balls in such a manner that they are urged at all times by gravity toward a delivery opening 21 which is provided in one of the side walls of the magazine 12 adjacent the bottom thereof. An inlet opening 22 is also provided adjacent the top of the magazine 12 in position to permit the ball 13 to be inserted on top of the uppermost tongue 18. Preferably a locked cap 23 is provided for the opening 22, so that unauthorized persons cannot have access to the interior of the magazine. The outlet opening 21 leads to the receptacle 16 so that balls 13 released from the magazine 12 drop into the receptacle 16 whence they can easily be removed by the operator merely by lifting the hinged lid 17.

75. Means are provided for releasing a predeter-

mined number of the golf balls 13, which number however is dependent upon the manner in which the machine is operated; that is to say, by operating the machine in one particular way, a certain number of golf balls may be released to the receptacle 16, and by operating it in another way another certain number of balls 13 will be released. This releasing mechanism, which is contained within the auxiliary housing 14, is best shown on Figs. 5 to 9, inclusive, comprising a rigid bar 31 mounted preferably at its ends on the opposed side walls 32 of the auxiliary housing 14 and extending closely adjacent and parallel to the back wall 33 of the magazine 12. A plurality of tubular guides 34 are rigidly mounted upon the bar 31, each of these extending preferably to the back wall 33 of the magazine 12 and having reciprocably mounted therein a pin 36, each of which is sufficiently longer than the associated guide 34 to permit it to extend, under certain conditions to be described hereinbelow, through the wall 33 and into the magazine and into the path of the golf balls 13 in their movement along the inclined plane of their support toward the delivery opening 21. Each of the pins 36 is provided with a shoulder 37 (see Fig. 9) and a coil spring 38 under compression between the shoulder 37 and that end of the guide 34 which is proximal to the magazine 12 continuously urging the pin 36 away from the magazine. In other words, the coil springs 38 are at all times urging the pin 36 or stop out of the path of the golf balls 13.

Behind the rod 31 and parallel thereto a shaft 41 is revolvably mounted, also preferably in the side wall 32 of the auxiliary housing 14. This shaft is continuously urged to rotate by means of a drum 42 upon which a tape 43, of metal or other material, is wound. A coil spring 44 is under tension between the outer end of the tape 43 and the back wall of the auxiliary housing 14, the parts being so arranged that the energy exerted by the spring 44 continuously urges the shaft 41 to rotate.

The shaft 41 carries a plurality of cams 46, one such cam being associated with and disposed in registry with each of the pins, or stops, 36. These cams 46 are so disposed upon the shaft 41 that their respective high points are progressively angularly offset from each other about the axis of the shaft 41. The direction of this offsetting is opposite to that in which the shaft is urged to rotate by the spring 44 as the distance of the cams 46 increases from the wall of the magazine 12 in which the delivery opening 21 is provided. In other words, when the cam 46 proximal to the wall in which the delivery opening 21 is so positioned that it engages its associate pin 36 and forces it into the magazine 12, the next adjacent stop has not quite reached its position of engagement with its associated pin, the stop 46 beyond that is still farther from its position of engagement with its associated pin, and so on.

Thus it may be seen that the distance through which the shaft 41 is permitted to rotate determines which of the stops 36 will be thrust into the magazine and into the path of the golf balls. The normal position for the shaft 41, i. e., the position assumed thereby when the machine is inoperative, is with the cam 46 which is proximal to the delivery opening 21 in engagement with its associated pin 36. For convenience during the further description, this cam will be identified by the numeral 47, and its associated stop or pin by the numeral 48.

An additional stop 51, similar to the stops 36

75

and 48 previously described, is supported at suitable elevation above the bar 31 by means of a bracket 52 mounted upon an arm 53 extending rigidly from the bar 31. The pin or stop 51 is pressed by a spring (not shown) in a manner similar to that of the previously described pins 36 and 48, being mounted in a guide tube 54 which is rigid with the bracket 51. Instead of being engaged by a cam, however, the pin 51 is adapted 10 to be pressed into operative position by means of an obliquely extending finger 56 which is rigidly mounted upon a vertically reciprocable rack 57 slidably mounted upon the rigid arm 53. The teeth 58 of the rack 57 are engaged with a pinion 59 which is carried by the shaft 41, the parts being so proportioned and arranged that when the shaft 41 rotates in that direction which causes either the cams 46 to engage their respective stops 36 in their order of those stops or their 20 distance from the wall in which the delivery opening 21 is provided, the pinion 59 will cause the rack 57 to be raised bringing the inclined finger 56 into engagement with its stop pin 51 at such time that after the last pin 36 carried by the horizontal bar 31 is extended and then retracted, the upper pin 51 will be pushed into operative position.

Whereas any appropriate spacing for the pins 48, 36 and 51 may be employed, that arrangement 30 which is preferred for the present modification can be best understood by reference to Fig. 1, which shows the first pin 36-a spaced from the pin 48 far enough to receive but one golf ball 13. The second pin 36-b is so spaced from the pin 36-a that two golf balls 13 are spaced therebetween, making a total of three balls between pin 36-b and the pin 48. The pins 36-b and 36-c accommodate four balls therebetween, thus making a total of seven balls between the pin 48 40 and the pin 36-c. The upper pin 51 is spaced a considerably greater distance from the pin 36-c, accommodating 11 balls therebetween, or a total of eighteen between the pin 51 and the pin 48.

The pins have been arranged to accommodate 45 balls therebetween in accordance with the above description inasmuch as the coin actuated mechanism is intended to be operated by coins of different denominations, in the present modification by a ten-cent piece, a twenty-five-cent piece, a fifty-cent piece and one dollar. The mechanism is so arranged, as will be described hereinbelow, that when a ten-cent piece is deposited, one ball will be delivered; a twenty-five-cent piece, three balls; a fifty-cent piece, seven balls, and a dollar, eighteen balls; the purpose being to urge the operator to use a coin of larger denomination because of the proportionally greater number of balls he receives for his money. The coin actuated mechanism consists of a plurality of arms 66, 67, 68 and 69, mounted for rocking movement about a vertically extending pintle 71, each of the arms 66 to 69, inclusive, is provided with a separate spring 72 urging the associated end of that arm toward the rack 57 and into position 55 above a stop 73 carried thereby. The spacing between the several arms 66 to 69, inclusive, is such that by removing the lowermost arm 66 from the path of the stop 73 the rack 57 is permitted to rise far enough to permit the shaft 41 to turn 60 far enough to remove the cam 47 from its engagement with the pin 48 and to cause the first cam 46 to push its associated stop pin 36-a into the magazine. This will release one golf ball 13. The spacing between the remaining arms 67, 68 70 and 69, is the same; thus when the two lower-

most arms 66 and 67 are both withdrawn from the path of the stop 73, the pin 48 will first be retracted, the pin 36-a will be extended and then retracted, and the pin 36-b will be extended and left extended, thus releasing three 5 golf balls. In a similar manner, withdrawal of the three lowermost arms 66, 67 and 68 will release the seven balls between the pin 48 and the pin 36-c, and retraction of all the arms 66, 67, 68 and 69 will release the entire eighteen balls 10 between the pin 48 and the pin 51.

Preferably a separate coin receiver is provided for each of the arms 66 to 69 inclusive. The coin receiver 76, associated with the lowermost arm 66, comprises a plate 77 having an aperture large 15 enough to receive a ten-cent piece therein, adapted to be brought into registry with a similar aperture 78 in the guide 79 through which the plate 77 is reciprocable. The inner end 81 of the plate 77 is bent upward far enough to engage only 20 the arm 66. Suitable mechanism (not shown) is provided for preventing movement of the plate 77 unless a coin of the proper denomination is employed.

The remaining arms 67, 68 and 69 are provided 25 with individual coin receivers 82, 83 and 84, respectively, which are similar to the receiver 76, except that their respective apertures are of appropriate sizes to receive twenty-five cents, fifty cents and one dollar respectively, and with 30 the further exception that their inner ends 86, 87 and 88, respectively, are adapted to engage two, three and four of the arms, respectively. Thus, for example, when the fifty-cent coin receiver is actuated, the three lowermost arms 66, 67 and 68 35 will be removed from the path of the stop 73. It is believed that the result of operation of each of the other coin mechanisms will be understood.

Means are provided for returning the parts to initial position for subsequent operation. In the present modification this return mechanism is actuated by the operator when he raises the cover 17 of the receptacle 16, which he must do in order to receive the golf balls which have been released from the magazine 12. As stated hereinabove, the cover 17 is mounted for pivotal movement. It carries an arm 91 (Figs. 2 and 10), so proportioned and arranged that when the cover 17 is raised the inner end of the arm 91 moves downward into engagement with the upper end 50 of the rack 57, preferably seating within a suitable socket 92 there provided and forces the rack downward. It is believed that the manner of operation of my improved dispensing machine will be apparent from the above description of 55 its constituent parts. Suffice it to say, therefore, that each time the machine is operated a number of golf balls, determined by the denomination of the coin employed, will be released from the machine to the receptacle 16 from which they can 60 be removed by the operator merely by raising the lid 17, and then when the operator raises the lid so as to secure the balls which he has purchased, the machine will be reset for subsequent operation.

65 I claim:

1. In a device of the character described, a magazine for storing a plurality of objects to be dispensed and having an outlet opening for delivery of said objects, means guiding said objects in a 70 predetermined path toward said outlet, a plurality of movable stops mounted adjacent the path of said objects in moving toward said opening, said stops being disposed at successively greater distances from said opening to receive a different 75

number of said objects between the stop proximal to said opening and each of the others of said stops, means yieldably urging all of said stops out of operative position, said proximal stop being 5 normally maintained in operative position, a shaft rotatably mounted adjacent said stops, a plurality of cams rigid with said shaft, each in position to engage one of said stops and force it into operative position, said cams being progressively angularly 10 offset with respect to each other about the axis of said shaft whereby they actuate said stops successively in their order of distance from said delivery opening, and means for rotating said shaft.

2. In a device of the character described, a magazine for storing a plurality of objects to be dispensed and having an outlet opening for delivery of said objects, means guiding said objects in a predetermined path toward said outlet, a plurality of movable stops mounted adjacent the path of 15 said objects in moving toward said opening, said stops being disposed at successively greater distances from said opening to receive a different number of said objects between the stop proximal to said opening and each of the others of said stops, means yieldably urging all of said stops out of operative position, said proximal stop being 20 normally maintained in operative position, a shaft rotatably mounted adjacent said stops, a plurality of cams rigid with said shaft, each in position to engage one of said stops and force it into operative position, said cams being progressively angularly 25 offset with respect to each other about the axis of said shaft whereby they actuate said stops successively in their order of distance from said delivery opening, means for rotating said shaft, a pinion carried by said shaft, a rack enmeshed with 30 said pinion and mounted for longitudinal reciprocatory movement, an abutment carried by said rack, a plurality of spaced detents normally disposed in the path of said abutment, means for moving a selected number of said detents out of 35 the path of said abutment, an additional stop mounted in position to extend into said path of said objects and spaced therealong the greatest distance of any of said stops from said delivery opening, means yieldably urging said additional 40 stop out of operative position, and means carried by said rack for actuating said additional stop only after all of said cams have released their respective stops.

30

3. In a device of the character described, a magazine for storing a plurality of objects to be dispensed and having an outlet opening for delivery of said objects, means guiding said objects in a predetermined path toward said outlet, a plurality of movable stops mounted adjacent the path of 45 said objects in moving toward said opening, said stops being disposed at successively greater distances from said opening to receive a different number of said objects between the stop proximal to said opening and each of the others of said stops, means yieldably urging all of said stops out of operative position, said proximal stop being 50 normally maintained in operative position, a shaft rotatably mounted adjacent said stops, a plurality of cams rigid with said shaft, each in position to engage one of said stops and force it into operative position, said cams being progressively angularly 55 offset with respect to each other about the axis of said shaft whereby they actuate said stops successively in their order of distance from said delivery opening, means for rotating said shaft, a pinion carried by said shaft, a rack enmeshed with 60 said pinion and mounted for longitudinal reciprocatory movement, an abutment carried by said rack, a plurality of spaced detents normally disposed in the path of said abutment, and means for moving a selected number of said detents out of 65 the path of said abutment.

4. In a device of the character described, a magazine for storing a plurality of objects to be dispensed and having an outlet opening for delivery of said objects, means guiding said objects in a predetermined path toward said outlet, a plurality of movable stops mounted adjacent the path of 70 said objects in moving toward said opening, said stops being disposed at successively greater dis-

tances from said opening to receive a different number of said objects between the stop proximal to said opening and each of the others of said stops, means yieldably urging all of said stops out of operative position, said proximal stop being 5 normally maintained in operative position, a shaft rotatably mounted adjacent said stops, a plurality of cams rigid with said shaft, each in position to engage one of said stops and force it into operative position, said cams being progressively angularly 10 offset with respect to each other about the axis of said shaft whereby they actuate said stops successively in their order of distance from said delivery opening, means for rotating said shaft, a pinion carried by said shaft, a rack enmeshed with 15 said pinion and mounted for longitudinal reciprocatory movement, an abutment carried by said rack, a plurality of spaced detents normally disposed in the path of said abutment, means for moving a selected number of said detents out of 20 the path of said abutment, an additional stop mounted in position to extend into said path of said objects and spaced therealong the greatest distance of any of said stops from said delivery opening, means yieldably urging said additional 25 stop out of operative position, and means carried by said rack for actuating said additional stop only after all of said cams have released their respective stops.

5. In a device of the character described, a magazine for storing a plurality of objects to be dispensed and having an outlet opening for the delivery of said objects, means guiding said objects in a predetermined path toward said outlet, a plurality of movable stops mounted adjacent the path 30 of said objects in moving toward said opening, one of said stops being proximal to said opening and the other stops being arranged at different distances therefrom along said path to accommodate a different number of said objects between said 35 proximal stop and each of said other stops, means for successively effecting withdrawal of said stops from said path in the order of their distance from said opening and for positively thrusting a stop further from said opening into said path before 40 withdrawal of any one of said stops is completed.

6. In a device of the character described, a magazine for storing a plurality of objects to be dispensed and having an outlet opening for the delivery of said objects, means guiding said objects in a predetermined path toward said outlet opening, a plurality of movable stops mounted adjacent the path of said objects in moving toward opening, one of said stops being proximal to said opening and the other stops being arranged at different distances therefrom along said path to accommodate a different number of said objects between said proximal stop and each of said other stops, means for successively effecting withdrawal of said stops from said path in the order of their distance from 50 said opening and for positively thrusting a stop further from said opening into said path before 55 withdrawal of any one of said stops is completed, and variable means for limiting the extent of action of said withdrawal-effecting means.

7. In a device of the character described, a magazine for storing a plurality of objects to be dispensed and having an outlet opening for the delivery of said objects, means guiding said objects in a predetermined path toward said outlet, a plurality of movable stops mounted adjacent the path of said objects in moving toward said opening, one of said stops being proximal to said opening and normally in operative position and the other stops being normally in inoperative position and ar- 75

5 ranged at different distances therefrom along said path to accommodate a different number of said objects between said proximal stop and each of said other stops, yieldable means urging each of said stops out of said path, positioning means for placing said stops into quantity selecting positional relation with respect to predetermined numbers of said objects, said positioning means comprising cam means for forcing said stops into

10 said path in number grouping selecting position, and means for actuating said cam means.

8. In a device of the character described, a magazine for storing a plurality of objects to be dispensed and having an outlet opening for the delivery of said objects, means guiding said objects in a predetermined path toward said outlet, a plu-

rality of movable stops mounted adjacent the path of said objects in moving toward said opening, one of said stops being proximal to said opening and the other stops being arranged at different distances therefrom along said path to accommodate a different number of said objects between said proximal stop and each of said other stops, yieldable means urging each of said stops out of said path, cam means for forcing said stops into said path, and means for actuating said cam means, said cam means being interconnected and arranged to force one of said stops into said path before the cam associated with the stops nearer to said opening move to releasing position.
